UNITED STATES PATENT OFFICE.

CHARLES J. KINTNER, OF NEW YORK, N. Y.

ELECTRIC RAILWAY.

SPECIFICATION forming part of Letters Patent No. 700,129, dated May 13, 1902.

Original application filed May 6, 1901, Serial No. 58,923. Divided and this application filed September 25, 1901. Serial No. 76,564. (No model.)

To all whom it may concern:

Be it known that I, CHARLES J. KINTNER, a citizen of the United States, residing at New York, in the borough of Manhattan, county 5 and State of New York, have made a new and useful Invention in Electric Railways, of which the following is a specification.

My invention is directed particularly to improvements in sectional-third-rail systems of electric railways, and this application is in part a division of a prior application filed by me in the United States Patent Office on the 6th day of May, 1901, and bearing Serial No. 58,923, and has for its objects, first, to provide a system of this type in which the sectional third rails or conductors normally disconnected from the current feeder or main are automatically connected to and disconnected from the same as a car or vehicle 15 passes over the route and to combine therewith automatic signals, the entire arrangement being such that front or rear end collisions are avoided; second, to provide an electric-railway system of the sectional third-rail 20 type with automatic signals so interconnected with the sectional third rails or conductors of the system that when any given sectional third rail or conductor is made alive signals will be displayed at the distant ends of the 25 system; third, to provide an electric-railway system with means for avoiding collisions at switches or side tracks where trains pass each other and to combine therewith automatic signals; fourth, to provide 30 an electric-railway system with means for preventing a car from approaching within a definite distance from either end of a draw or turn bridge when the latter is moved from its normal or closed position and to combine therewith automatic signals; fifth, to provide 35 an electric-railway system with means for preventing a draw or turn bridge from being moved from its normal or closed position after a car has approached within a definite distance from either end thereof and to combine 40 therewith automatic signals; sixth, to provide

an electric-railway system of the sectional-third-rail type with signal apparatus operatively controlled by electromotive devices and to combine therewith branch circuits and 55 switches adapted to enable a lineman to test the signals at any and all times or to leave any signal set temporarily at "danger;" seventh, to provide a sectional-third-rail system which shall automatically afford absolute 60 safety in the movement of cars or trains through the agency of devices, hereinafter described, embodying all of the details of construction shown in the accompanying drawings, the essential points of novelty of my in- 65 vention being particularly pointed out in the claims at the end of this specification.

For a full and clear understanding of the invention, such as will enable others skilled in the art to construct and use the same, reference is had to the accompanying drawings, in which—

Figure 1 is a diagrammatic view illustrating three complete successive sections of a third-rail system embodying my improvements, a 75 car being shown in side elevational view passing over the central section, two of the signals shown at "danger," two at "safety," and the bases of the semaphore-posts which support the signals at the bottom of the drawings with their tops broken away. Fig. 2 is a similar diagrammatic view illustrating further features of my improvements embodying a side track, a turn-bridge, and a road-crossing gate with automatic signals for use in connection with said parts. Fig. 3 is a plan view of the features illustrated in Fig. 1, a crossing road being shown in dotted lines, road-crossing gates in closed position, and glowing signal-lamps being added to the structural 80 feature of Fig. 1. Fig. 4 is an enlarged transverse sectional view taken on the line 2 2, Fig. 3, and as seen looking thereat from left to right in the direction of the arrows. Fig. 5 is an enlarged sectional view taken through 85 the upper part of one of the semaphore-posts and the hood or housing at the top thereof on the line x x, Fig. 6, and as seen looking thereat from left to right in the direction of the arrows, the two diametrically opposite positions of the semaphore-arm and signal-lamps 90 being shown in dotted lines on the right and

left. Fig. 6 is a transverse sectional view taken on the broken line y y , Fig. 5, and as seen looking thereat from right to left in the direction of the arrows, this sectional view 5 illustrating also the manner of supporting the main journal of the semaphore-arm, the propelling-motor for the semaphore and its interconnected gearing and the manner of sustaining said parts all being shown in side elevational view within the hood or housing.

It is to be noted that I have illustrated the tram-rails and all of the conductors of the system which convey the working current to the motors on board the cars in heavy black 15 lines and all of the switch-operating and signaling circuits which convey the current to the switch-controlling magnets and to the signals in light black lines.

Referring now to the drawings in detail, in 20 all of which like letters and numerals of reference represent like or equivalent parts wherever used, and first to Fig. 1, 1 represents the current feeder or main connected to the positive pole of the power-house generator, 25 (not shown,) and 4 one of the tram-rails, bonded in the usual manner and connected to the negative pole thereof. 3 3 3, &c., represent the sectional third rails or conductors of the system, normally disconnected from the 30 current feeder or main and connected at each end by conductors 7 7 to yielding conducting-terminals t^2 t^3 , &c., of the switches m' m^2 , m' m^2 being switch-operating magnets for causing the yielding terminals t^2 t^3 to be locked 35 or connected directly or positively with the current feeder or main through locking-armatures t t' t t' , &c., by short branch feeders or conductors 2 2 2, connected directly to the feeder. The electromagnets m' m^2 m' m^2 , 40 &c., are included in short branch circuits 11, connected each at one end to a short circuit-closing rail or contact c or c' , located near the ends of the adjoining third rails 3 3, &c., and on opposite sides thereof, the 45 other ends of said circuits being connected directly to the tram-rail or return-conductor 4. 5 6 5 6 are signaling and releasing conductors connected to the opposite ends of each sectional third rail or conductor and extending 50 in opposite directions to the switch-boxes at the ends of the adjacent sectional third rails or conductors, where they are connected through branch conductors to the releasing-magnets and signals and to earth or return, so as to constitute safety-circuits, as 55 will be described later on.

In Figs. 1 and 2 I have illustrated successively five complete third-rail sections, said sections being indicated by the letters A, B, 60 C, D, and E. The car C is represented as passing from left to right in the direction of the arrow over the section B. tr represents a flanged trolley-wheel resting upon the third rail 3, and 13 a conductor running therefrom 65 to the motor MO on board of the car, said motor being connected in the usual manner through a controller K, as illustrated in Fig. 1.

4, to the car-wheel w and to the tram-rails or return-conductor 4. P P' P^2 P^3 P^4 P^5 represent semaphore-posts, and S S' S^2 S^3 , &c., 70 semaphore-arms journaled in the top thereof and operatively connected each with a driving gear-wheel g , which meshes with a pinion p , carried by the armature-shaft of an electric motor M or M' or M^2 , &c., said motors being 75 each preferably provided with two pairs of field-magnets f f and f' f' and two pairs of commutator-brushes for the armatures thereof, the windings of the pairs of field-magnets and their connections with the commutator-brushes being such as to give to the armatures rotary motion in opposite directions when used independently, as will be described in connection with the description of the mode of operation. 8899 represent pairs of branch 85 conductors running from the ends of the conductors 5 6 5 6 and to the field-magnets f f and f' f' and also to signaling-lamps l l , supported by the short arm of the semaphore-signals. 12 12 are return-circuits running 90 from the lamps and the motors directly to the tram-rail or return-conductor 4. 24 24 24 and 25 25 25 are branch circuits, and zzz are switches for testing the signals or for setting the same to display "danger" temporarily, 95 said circuits and switches being shown in dotted lines.

The operation of the system as thus far described is as follows: Suppose the car to be traveling from left to right in the direction 100 of the arrow and passing over section B. Under this condition current is flowing from the current feeder or main 1 through the branch feeder 2 to the locking-armature t , yielding conducting-terminal t^2 , branch conductor 7, 105 third rail 3, to the flanged trolley or collector 14, by the conductor 13 to the controller K, (see Fig. 4,) motor MO, car-wheels w , to the tram-rails or return-conductor 4, thus furnishing current to move the car in the direction shown. At the same time current flows by the signaling and releasing conductor 5 to the rear by conductor 8 to one coil of the releasing-electromagnet m at the distant end 110 of section A, adjoining the third-rail section 115 B, thence to the tram-rail 4 to the negative pole of the generator, thus magnetizing both legs of the magnet m in such manner as to hold the armatures t t' in their upper positions. An additional branch current flows 120 by the multiple or branch conductor 9 through the field-magnets f f , their corresponding pair of commutator-brushes and the armature of the motor m , by the return-conductor 12 to the tram-rails 4 and negative pole of the 125 generator, thus causing the armature to rotate in this instance from left to right in the direction of the hands of a watch, thereby imparting motion to the gear-wheel g in a reverse direction, as shown by the arrow, and 130 causing the semaphore-arm S to assume an exposed position at right angles to the post P , as illustrated in plan view at the extreme left-hand end of Fig. 3 and in elevational

view in Fig. 4. A multiple or branch circuit is also closed from the conductor 9 through the lamp l and the return-conductor 12, thereby causing the lamp to glow and to indicate "danger" through an opening o in the top of the semaphore-post. (See also Figs. 3, 4, and 5.) An additional branch circuit is also closed from the right-hand end of the third rail 3, over which the trolley tr is moving by the signaling and releasing conductor 6 to the distant end of the next section in advance, where the circuit connections through the branch conductors 8 and 9 are effected, in the first instance, to the left-hand coil of the releasing-magnet m and in the second instance to the field-magnets $f' f'$ and armature of the motor M^3 , and also through the lamp l' and by return-conductor 12 to earth, thus causing the locking-armatures $t t'$ at this point to be held in their upper positions and at the same time causing the armature of the motor M^3 to be rotated in a direction the reverse of the hands of a watch, thereby imparting motion to the gear-wheel g in the direction of the hands of a watch, as shown by the arrow, and elevating the semaphore-arm S^3 to the position shown, pointing to the left, at the same time bringing the lamp l' , which is caused to glow, in this instance opposite the opening o' in the signal-post. (See also Figs. 3, 4, and 5.) It will be apparent, therefore, that during the time the car is passing over the sectional third rail 3, upon which the trolley tr is now seen upon section B, no car can receive current from a section in the rear nor can any car coming in the opposite direction receive current from a section in advance, owing to the fact that both of the pairs of locking-armatures m at the distant ends of the sections A and C are held in their upper or inoperative positions, as shown, and out of the path of the free ends of the yielding conducting-terminals $t^2 t^3 t^2 t^3$, so that should any train enter section A from the left no working current will be available, and in like manner should any train enter section C from the right no working current will be available. It will also be noticed upon examination of Figs. 3 and 4 that to any motorman entering the section A from the rear the semaphore-arm S appears on the right, thus giving indication always of the fact that danger is in front; also, that to any motorman entering section A in the opposite direction the semaphore-arm S^3 appears on the right, thus giving indication always of the fact that danger is in front. When the car approaches the near end of section C, the flanged trolley tr closes the circuit between the third rail 3 and the corresponding circuit-closing rail c , thereby conveying current from the live third rail through the conductor 10, magnet m' to the tram-rail or return-conductor 4, thus causing the yielding conducting-terminal t^2 at the entrance to section C to be drawn into its hooked or locked position. At the same time circuits are closed through the signaling and re-

leasing conductors 5 and 6, with the third rail 3 between the sections C and D in each direction, releasing the terminal t^2 , held by the locking-armature t at the entrance of section B, and displaying danger-signals at the entrance of section B in the rear and at the distant end of section D in advance, as before. As the car advances, therefore, each sectional third rail in the rear and in advance of that over which it is at the time passing will be rendered dead or inert so long as said car remains upon the section and danger-signals will be displayed at the opposite ends of the adjacent sections, the semaphore-arms giving indication for day signals and the lamps for night signals. At the same time as each car enters a section the semaphores at the distant ends of the adjacent sections are released and allowed to return by gravity to safety or normal position and the lamps cease to glow.

The conductors of the entire system, except the current feeder or main and the short branch feeders 2 2 and armatures $t t'$, all of which are located in the switch-boxes, are normally without electrical current potential, and only those conductors have electrical current potential which are connected to the current feeder or main through some one of the conducting-terminals t^2 or t^3 , and also should any sectional third rail or conductor 3 be left connected to the current feeder or main through one of the yielding conducting-terminals t^2 or t^3 the locking-armatures $t t'$ of the switches at the distant ends of the adjacent sectional third rails or conductors will both be held in their upper positions and the corresponding semaphore signals or lamps, or both, be displayed, so that a motorman whose car is approaching in either direction will be given warning of the fact and his car will stop for lack of current if he fails to observe the signal as soon as it passes the same. In order to run cars in a reverse direction over the same track, it is only required to reverse the reversible trolley tr , as will be apparent on inspection of Fig. 4 of the drawings, by lifting it through the agency of an operating hand-wheel hw and rotating it through an arc of one hundred and eighty degrees, then lowering it into position, so that the flange is in a reverse position from that shown in the drawings. When the trolley is in this position, each time that it passes one of the switch-boxes SB, sustained by the insulator I, it will close circuit to the proper one of the circuit-closing circuits c' and conductors 11 to the corresponding magnet m^2 and effect the proper connections for connecting the sectional third rails or conductors in advance of the car as it operates the same. It will also be apparent that under no condition can a car leave a sectional third rail in either direction without disconnecting it from the current feeder or main after it has advanced a definite distance or passed the next switch-box, this owing to the fact that the

locking-armatures t t' are always operated when either one of the coils connected to the signaling and releasing circuits 5 and 6 is connected in circuit, each of said coils having sufficient magnetizing capacity to fully saturate the core of the magnet.

In Fig. 2 of the drawings I have illustrated a continuation of the system embracing additional sectional third rails or conductors, switches, signals, &c., which are similar in all respects to those already described in connection with Fig. 1. I have also illustrated in this figure, in section D, the application of my invention in connection with a draw or turn bridge, showing how collisions and accidents are avoided at these places. I have also illustrated in this figure of the drawings, at the extreme right-hand end thereof, how my invention makes it possible to use in connection therewith automatically-controlled road-crossing gates, which shall prevent foot-passengers and vehicles from crossing when a car has entered the section and which shall also give preliminary warning of that fact.

Referring to this figure of the drawings in detail, 14 represents a single side-track tram-rail corresponding to the tram-rail 4 and provided with the usual switching arrangements (not shown) and 15 the corresponding side-track third rail or conductor, only one tram-rail being shown in this figure of the drawings and also in Fig. 1 for the purpose of avoiding unnecessary complications thereof.

In Fig. 2 of the drawings, which, as before indicated, illustrates, in effect, a continuation of the system shown in Fig. 1, only two sets of switching and signaling apparatus for the systems are shown, the side track, as already described, and the turn-bridge tb being located in this section. The circuit connections to the switching-magnets, the yielding conducting-terminals, the releasing-magnets, the signal-operating motors, and the lamps are the same as illustrated in Fig. 1, except that I provide additional circuit connections for the third-rail section D, embracing the side track and draw or turn bridge and also the road-crossing gate, as will now be described.

14 represents, as before indicated, the tram-rail for the siding, and 15 the corresponding third rail for the trolley. c^2 c^3 are the circuit-closing rails or contacts near the center of the third-rail siding, similar to the corresponding circuit-closing rails c c' referred to in connection with Fig. 1, except that both of said circuit closing rails or contacts c^2 are connected directly to a single safety and signal conductor 16, which branches and runs in opposite directions to independent coils around one leg of the core of each of the releasing-magnets m m and thence to the tram-rail or return-conductor 4. These coils might, if preferred, be placed around the central yoke, which joins the other two coils included in the releasing-circuits 5 and 6. tb represents in dotted lines a draw or turn bridge, and 3 that section of the third rail for the section

D which is carried or sustained by the bridge, the opposite ends of said rail being adapted to make good electrical contact with contact-plates e e at the opposite ends thereof when the bridge is closed, so as to constitute one continuous third rail for the section D. It will be understood, of course, that corresponding tram-rails are carried by the bridge and at the ends of the tram-rails 4 on opposite sides of the river or space to be bridged, together with a current feeder or main 1. The signaling and releasing conductors 5, 6, and 16 are connected together by corresponding conductors and all inclosed in a cable located in the bed of the river. s' w' is a two-arm switch having its pivot-point connected by a conductor 17 directly with the current feeder or main 1 and its free end adapted to make contact with either of two contacting plates connected directly to a conductor 18, which in turn is connected to the safety and signaling conductor 16, the arrangement being such that when the bridge is closed the contacting part of the switch s' w' rests in a central position with relation to the two contacts and out of contact with both. i represents a switch-operating pin carried at one end of the bridge, and R is a locking-notch in the other end thereof adapted to receive the hooked end of the locking armature-lever when the bridge is closed, said armature-lever being under the control of an electromagnet lm included in a branch circuit 20 between the third rail 3 and the tram-rail or return-conductor 4. sb is an alarm bell or signal located in multiple circuit with the magnet lm and is adapted to ring or give an advance indication of danger when the third-rail section D is connected to the current feeder or main at either end. m' o' is an electric motor for moving the bridge, its armature being connected to a pinion geared with a large gear-wheel on the under side of the former, said motor being included in a circuit 21, one end of which is connected directly to the tram-rail or return-conductor 4 and the other to the current feeder or main 1. sw is the operating-switch, and PS is a pole-changing switch for reversing the direction of motion of the motor in a manner well understood by those skilled in the art. a is an armature-lever located in the circuit 21 and adapted to be operated by an electromagnet sm , located in a branch circuit 19, connected at its opposite ends to the sectional third rail 3, which includes the bridge and the tram-rail or return-conductor 4.

Referring now to the road-crossing gate illustrated on the extreme right of Fig. 2 and also in duplicate in Fig. 3, G represents the gate, which is a swinging arm of the usual type pivotally supported to a post s^3 and provided with the usual weight on its shorter arm for restoring it to its upper or vertical position. This gate is operated by an electric motor located within the post s^3 and included in a branch circuit 22 between the

third rail 3 and the tram-rail or return-conductor 4. t^3 is a danger signal or lamp included in a multiple branch circuit 23 around the motor which controls the movement of the gate, and $s^2 w^2$ is a switch for disconnecting the lamp when desired. This road-crossing gate is located at the middle of the third-rail section where the road crosses, as clearly illustrated in Fig. 3, where two such gates are shown in closed position. The operation of these features of the invention, as illustrated in Figs. 2 and 3, is as follows: Referring first to the draw or turn bridge, suppose the attendant to be turning the bridge from left to right in the direction of the hands of a watch, as shown by the arrow, the switch sw being closed and the motor $m' o'$ effecting the movement as indicated. At the instant that the ends of that part of the sectional third rail 3 carried by the bridge left the contact-plates $e e$ the pin i , carried at the left-hand end of the bridge, acted upon the upper or left-hand arm of the two-armed switch $s' w'$, causing it to be snapped into the position shown, with its free end contacting upon the lower one of the two contact-plates. Consequently a circuit was closed from the current feeder or main 1 by the branch conductor 17, through the switch $s' w'$, conductor 18, conductor 16 in opposite directions to the independent coils about the cores of the magnets $m m$. At the same time multiple branch circuits were closed through the signals $t^2 t^3$, thus giving an especial indication of danger at the distant end of the section D. Should a car advance now in either direction toward the section D, danger-signals will be seen at $t^2 t^3$. Should the motorman fail to note the proper signal, no current will be received from either end of the sectional third rail 3 when his car passes the switch for effecting connection with that rail, for the reason that the locking-armatures $t' t'$ at both ends of this section are held out of operative relation with the yielding conducting-terminals $t^2 t^3$. Therefore the car will stop for lack of current and no working current can be received until the armatures $t' t'$ are released. On returning the bridge to its normal or closed position the pin i acts upon the lower or right-hand arm of the snap-switch $s' w'$ and interrupts the circuit of the branch conductors 17 18. At the same instant that part of the sectional third rail 3 carried by the bridge completes the circuit of the entire third rail for section D at the points $e e$, so as to make the third rail continuous. Consequently the locking-armatures $t' t' t' t'$ at both ends of the section D will be restored to their normal or operative positions and the danger-signals will cease to give indication of danger. In the event of a car passing the switch next adjacent to the bridge on either side thereof when the latter is open it will of course be understood that after the bridge is closed it will be necessary to operate in the proper direction manually that one of the terminals t^2 or t^3 in the proper switch-box to

permit the motorman to advance in the desired direction. Should the bridge be rotated in a reverse direction, the switch $s' w'$ will obviously close the circuit in a manner already described, its free end contacting with the upper one of the contact-plates. The bridge being closed, suppose now that a car enters section D in either direction. The flange of the trolley acting in the manner already described will close the circuit through the closing rail or contact c or c' and conductor 10 or 11 to the proper switch, operating the magnet m' and connecting the sectional third rail 3 to the current feeder or main. When this is effected, current will flow from the third rail 3 of the section D through the branch conductors 20 and 19 between the third rail and the tram-rail or return conductor 4, thus causing the electromagnet lm to lock the turn-bridge tb through the agency of its armature-lever, also causing the alarm-bell sb to be rung continuously or any other alarm to be given, so as to warn the bridge attendant that a car is on the section. At the same time the electromagnet sm causes the armature-lever a to be drawn into its forward position, thereby interrupting the circuit of the motor $m' o'$, so that should the bridge attendant attempt to operate the bridge by closing the switch sw he will be prevented from doing so for three reasons: first, because the bridge is locked; second, because the source of power is disconnected, and, third, because a continuous alarm is given of the fact that a car is on the section. Suppose now it is desired to have two cars pass each other at the siding 14. The first train to arrive upon the section D will of course maintain control of that section and of the sections in the rear and in advance, as already indicated in connection with Fig. 1. When the car reaches the siding 14, it will be switched in the usual way upon said siding, and as it passes the center thereof the flange of the trolley tr in passing in either direction will close the circuit between the siding trolley-rail 15 by the conductor 16 to the electromagnets $m m$ at the distant ends of the section, thereby releasing the yielding terminals t^2 or t^3 , which had been connected to the current-feeder when the car entered the section. This will be effected as the car passes by the circuit-closing rails or contacts c^2 by its momentum. It will be understood, of course, that the danger-signals, which are controlled by the sectional conductor of section D, will be returned to "safety" when the proper terminals $t^2 t^3$ are released as the trolley passes the conductor or contact c^2 . The car coming in the opposite direction may now advance and pass the car upon the siding. After it has passed out of the next section in advance in either direction, so that the semaphores have returned to "safety," the proper terminal t^2 or t^3 may be actuated in an adjacent switch-box and the motorman may proceed on his way as before.

Referring now to Fig. 3, I will describe

the operation of the road-crossing gates. In this instance the car has just entered section B. The road-crossing gates G, as before indicated, are both in the middle of the section. 5 When the car entered the section, the third rail 3 was made alive, as has already been described in connection with Fig. 1. Consequently branch circuits were closed from the sectional third rail 3 through both of the motors in the posts s^3 s^3 , and multiple branch circuits were closed through the lamps l^3 l^3 , as will be apparent on inspection of Fig. 2. Therefore the motors caused both of the gates to be rotated to their lower positions and the 10 lamps l^3 to glow continuously. As the gates descend alarm-bells b (see Fig. 2) of well-known pattern are actuated continuously mechanically in the usual way, thus giving warning to foot passengers and persons on horseback or with vehicles that a car is entering the section. The gates G both remain closed and the lamps l^3 continue to glow until the car passes wholly out of the section in either direction, when they are released by the act 15 of releasing the sectional third rail 3 from its connection with the current-feeder. Both gates therefore return to their normal or upper positions through the agency of weights in the usual manner. During the day-time 20 the switches s^2 w^2 may be opened by a track-walker, and it may here be added that in like manner similar switches might be provided in switch-boxes at the bases of the semaphore-posts for enabling a track-man to disconnect the lamps during the day-time, such matters being well within the skill of those versed in the art.

Referring now to Figs. 5 and 6, I will describe in detail the construction of my novel 25 semaphore-signal, which is illustrated in these figures in enlarged views. The semaphore-post is made properly of two broad flat timbers located side by side and at proper distances from each other to admit of the free 30 swinging of the semaphore-arm S, said arm being supported by a shaft s, journaled at J in one side of the semaphore-post and an additional journal-bearing J' in the hood or housing H. The shaft s is provided, preferably, with ball-bearings for both journals. H is a hood or housing made, preferably, of 35 cast metal and having two compartments, one for the signal-lamp and the other for the motor M, said hood or housing being secured, as shown, directly to the upper end of the 40 semaphore-post by bolts or screws. Upon the shaft s is secured a large gear-wheel g, meshing with the pinion p of the motor M, the motor being secured, as shown, in the 45 upper part of the hood or housing. D' is a door for the hood or housing hinged at its lower side near the bottom thereof and provided with a ledge L, adapted when the door is open to rest against a similar ledge L', so 50 that said door constitutes, in effect, a shelf for holding tools or materials for use in connection with repairs, &c. A latch or lock

for the door is provided, as shown, for the purpose of holding it in closed position. d is a wooden cross-arm secured at right angles 55 to the upper end of the semaphore-arm and adapted when the latter hangs in its normal position to close the lower end of the hood or housing in such manner as to prevent birds or other animals from building nests or 60 otherwise interfering with the free operation of the signal. The signal-lamps l l' are preferably incandescent lamps of red glass and are carried directly by the short arm of the semaphore, the wiring thereto being effected 65 in such manner as to allow the latter to move with absolute freedom and to assume when released its normal or vertical position, so that it is absolutely concealed between the two 70 sides of the post and so that the lamps are fully 75 protected from all sources of destruction—such as mischievous boys or meddlesome persons. o and o' are holes in the opposite 80 faces of the two parts of the semaphore-posts and located below the cross-arm d, when the 85 semaphore assumes its normal position, one for the lamp l and the other for the lamp l', the arrangement being such, as will be apparent 90 on inspection of Fig. 3 of the drawings, that when the semaphore-arm S is rotated in one 95 direction one of the lamps will be visible on one side only of the post and the other lamp when the semaphore is swung in the other direction on the other side only thereof. Such a semaphore is absolutely free from danger of being 100 clogged with snow, sleet, or ice, is kept normally concealed within the post, so that it maintains its original color and cannot be marred, defaced, or rendered inefficient. It 105 will also be apparent that by reason of its being normally always concealed and protected it will maintain the bright red color which red-painted signals should maintain, and therefore be capable of always giving the best results. It will be understood, of course, that the 110 motor M or other electromotive device causes the semaphore-arm to be raised to its extreme limit until the lateral edge thereof strikes the hood or housing H and will hold it in this position until demagnetized, at which time it 115 will return by the action of gravity to its concealed position. No claim is made in the present application to this especial form of signaling apparatus, and it is only shown herein to illustrate the preferred form of signal to 120 be used in connection with my novel safety system of electric railways, nor is any claim made herein to the road-crossing gates and their operative connections. (Illustrated in 125 Figs. 2 and 3.)

In Fig. 1 of the drawings I have illustrated in dotted lines a series of branch circuits 125 and switches z, adapted to test the condition of the signals. These switches will of course be properly located in switch-boxes 130 under lock and key at the base of the semaphore-posts P P', &c., and it will be readily understood that by turning the switch z either to the right or left the motors and lamps are

connected in circuit with the current feeder or main, thereby giving evidence of the operative condition of the signals. If it is desired to set any signal temporarily to indicate "danger," this of course may be effected in the same manner.

I do not limit my invention to the especial details of construction illustrated in the accompanying drawings and hereinbefore described, as many of the features thereof are of a generic nature, and my claims are to be construed as of the most generic scope in relation thereto. To illustrate, in place of the semaphore-arms S S' S² S³, &c., an alarm-bell may be located in the hood or housing and actuated continuously by the motor M or M', &c., so long as the sectional third rail connected with said motor is energized or made alive, thus giving continuous audible signals, my claims being designed to be of such scope as to include all such obvious modified forms of signaling apparatus.

Although I have illustrated my invention as applicable especially with electric railways of the third-rail type where the third rails or conductors 3 are supported by insulators I, carried by the ties T', (see Fig. 4,) the invention may obviously be applied in connection with overhead or suspended conductors, such as are in well-known and general use, or the system may, if preferred, be a compound system, where the overhead conductors are divided into sections through villages and the third-rail sectional conductors utilized in the country, all such obvious modifications being well within the skill of those versed in electric railways. In place of the motors M M', I may use any type of equivalent electromotive devices for controlling the movements of the semaphore-arms—as, for instance, electromagnets, solenoids, &c.—such means being preferable when the semaphore-arms are light or substantially balanced by counterweights.

I make no claim in the present application to a safety system of electric railways embodying a current feeder or main, a series of sectional conductors normally disconnected therefrom, switching devices for connecting said conductors to and disconnecting them from the current feeder or main, and releasing-electromagnets included in circuits normally without current potential, the arrangement being such that the sectional conductors immediately in the rear or front of any given sectional conductor may be rendered dead or inert, nor to the application of this principle in connection with crossing-tracks, turn-bridges, and sidings or switches, as these features constitute the subject-matter of the original application of which the present application is in part a division, the present application being directed, in so far as this divisional feature is concerned, to the before-mentioned features combined with the additional features of signaling mechanism.

Having thus described my invention, what

I claim, and desire to secure by Letters Patent of the United States, is—

1. A safety system of electric railways embracing a current feeder or main, a series of sectional third rails or conductors normally disconnected therefrom and interlocking switching mechanism for positively connecting said sectional conductors to the current feeder or main as a car or vehicle passes by or over the same; in combination with safety-circuits, two for each sectional third rail or conductor, said safety-circuits including devices for releasing the interlocked conducting-terminals of the switches and signaling devices, and so connected to the power-house generator as to be normally without electrical current potential, substantially as described. 75

2. A safety system of electric railways embracing a current feeder or main and a series of sectional third rails or conductors normally disconnected therefrom; in combination with interlocking switching mechanism for positively connecting said sectional third rails or conductors to the current feeder or main and disconnecting them therefrom; together with a series of danger-signals, one for each sectional third rail or conductor, said danger-signals being connected permanently in circuit with said sectional third rails or conductors, and all of the conductors of the system, except the current feeder or main, being normally without current potential, substantially as described. 85

3. A safety system of electric railways embracing a current feeder or main, a series of sectional third rails or conductors normally disconnected therefrom and switching mechanism having conducting-terminals for connecting said sectional conductors to the current feeder or main as a car or vehicle passes by or over the same; in combination with releasing-electromagnets for the conducting-terminals of the switches, the individual coils of said releasing-magnets being included in circuit with safety-circuits normally without current potential and running in opposite directions and connected to earth and to the adjacent ends of adjoining sectional third rails or conductors; together with signaling mechanism included also in the safety-circuits, substantially as described. 100

4. A safety system of electric railways embracing a current feeder or main, a series of sectional third rails or conductors normally disconnected therefrom and switching mechanism for connecting said sectional conductors to and disconnecting them from the current feeder or main as a car or vehicle passes by or over the same; in combination with a series of safety-circuits, two for each sectional third rail or conductor, said safety-circuits being connected directly to the opposite ends of each of said conductors and extending to the opposite ends of the sectional third rails or conductors immediately in the front and rear thereof; together with signaling de- 115 120 125 130

vices included in said safety-circuits, substantially as described.

5. A system of electric railways embracing a current feeder or main; a series of sectional third rails or conductors normally disconnected therefrom and a series of electromagnetic switching devices for positively connecting and locking said sectional conductors to the current feeder or main as a car passes by or over the same; in combination with additional conductors normally without current potential and including electromagnetic devices for releasing the conducting-terminals of the switches; together with signaling devices included in circuit with said releasing devices for indicating the electrical condition of the sectional third rails or conductors, there being one such signaling device for each sectional third rail or conductor, substantially as described.
10. A system of electric railways embracing a current feeder or main, a series of sectional third rails or conductors normally disconnected therefrom, and a series of electromagnetic switching devices for connecting said sectional conductors to the current feeder or main as a car passes by or over the same; in combination with additional conductors, two connected to each sectional third rail or conductor, said additional conductors including electromagnetic devices for releasing the conducting-terminals of the switches and signaling devices; said additional conductors being normally without current potential, substantially as described.
15. A system of electric railways embracing a current feeder or main and a series of sectional third rails or conductors normally disconnected therefrom; in combination with electromagnetic switching devices for connecting said sectional third rails or conductors to the current feeder or main; together with electromagnetic releasing devices for disconnecting them therefrom and a series of danger-signals connected permanently in circuit with the sectional third rails or conductors, the circuits including the danger-signals being normally without current potential, substantially as described.
20. An electric-railway system embracing a current feeder or main; a series of sectional third rails or conductors normally disconnected from the current feeder or main, and a siding having a third rail or conductor electrically connected with one of said third rails or conductors; in combination with switching devices for connecting the sectional conductors to and disconnecting them from the current feeder or main; together with signaling devices, and circuit connections between the siding third rail and the aforesaid switching devices, substantially as described.
25. A safety system of electric railways embracing a current feeder or main; a series of sectional third rails or conductors normally disconnected therefrom and switching mech-

anism for connecting said sectional conductors to the current feeder or main and disconnecting them therefrom as a car or vehicle passes by or over the same; in combination with a drawbridge carrying a sectional third rail or conductor and circuits and circuit connections between the same and one of the sectional third rails or conductors; together with signaling mechanism operatively included in circuit with the sectional conductor adjacent to the bridge and with the current feeder or main, substantially as described.

30. An electric railway including a draw or turn bridge therefor; in combination with circuits and circuit connections so arranged that when a car approaches either end of said bridge within a definite distance the latter is locked or held so that it cannot be disturbed until after the car has crossed the bridge; together with one or more signals for giving continuous indication of the fact that a car is near or upon the bridge, substantially as described.

35. An electric railway of the sectional-third-rail type embracing a current feeder or main; a series of sectional third rails or conductors; switching devices for connecting the sectional conductors to the current feeder or main and signaling devices for indicating the electrical condition of the sectional third rails or conductors; together with branch circuits and switches adapted to connect the signaling device directly with the current feeder or main, or to maintain the same in temporary connection therewith, substantially as described.

40. An electric railway embracing a current feeder or main; a series of sectional third rails or conductors normally disconnected therefrom; a series of semaphore-signals operatively connected with electromotive devices for controlling their movements; in combination with branch circuits and switches adapted to connect the electromotive devices directly with the current feeder or main, substantially as described.

45. A system of electric railways embracing a current feeder or main, a series of sectional third rails or conductors normally disconnected therefrom, and a series of switching devices for connecting said sectional conductors to the current feeder or main as a car passes by or over the same; in combination with additional conductors, two for each sectional third rail or conductor, said additional conductors including electromagnetic devices for releasing the conducting-terminals of the switches and electromotive devices operatively connected with semaphore-signals, substantially as described.

50. An electric railway embracing a current feeder or main; a series of third rails or conductors normally disconnected therefrom; a series of switching devices for connecting said sectional conductors to and disconnecting them from the current feeder or main; a series of releasing-circuits operatively con-

nected with the switching devices and permanently in circuit with the sectional conductors; in combination with a series of semaphore signals operatively connected with 5 electromotive devices included in the before-mentioned releasing-circuits, said semaphore signals being adapted to move in opposite directions, substantially as described.

In testimony whereof I have signed my name to this specification in the presence of 10 two subscribing witnesses.

CHARLES J. KINTNER.
